UNITED STATES PATENT OFFICE

JOHN E. RADIGAN, OF DETROIT, MICHIGAN, ASSIGNOR TO BOHN ALUMINUM & BRASS CORPORATION, OF DETROIT, MICHIGAN, A CORPORATION OF MICHIGAN

APPARATUS FOR FORMING MOLDS

Application filed April 7, 1930. Serial No. 442,331.

The invention relates to the forming of molds of molding material, such as sand and the like, and refers more particularly to the method of and apparatus for forming these 5 molds. One of the objects of the invention is to provide an improved method of compacting the molding material to uniformly compact this material. Another object is to so construct the apparatus that it will uniformly 10 compact the molding material and it may be operated to secure high production of uniformly good molds. A further object is to so construct the apparatus that the table for supporting the pattern and flask may be jolted to compact the molding material and 15 may be rolled over to facilitate removal of the pattern from the mold. Still other objects reside in the novel features as more fully hereinafter set forth.

20 In the drawing:—

Figure 1 is a front elevation, partly in section, of an apparatus illustrating an embodiment of my invention;

Figure 2 is an end view thereof;

25 Figure 3 is a perspective view of the gauging frame for the molding material.

The mold jolting and ramming apparatus has the frame 1 upon which is vertically reciprocably mounted the jolt table 2 guided by 30 suitable means such as the guide pins 3 extending vertically upward from the frame and slidably engaging bushings 4 in the jolt table. 5 is the table for supporting the pattern 6 and the flask 7, this table being located 35 above the jolt table 2 and having at its ends the upwardly extending arms 8, each of which is provided at its upper end with the transverse trunnion pin 9 engaging in the vertically extending slot in the adjacent 40 trunnion 10, which extends above the adjacent end of the frame 1 and is vertically reciprocable relative thereto. This table 5 is of the roll-over type, it being adapted to be swung about its trunnion pins. The base 11 of this 45 table is adapted to be engaged by the jolt table 2 to jolt and ram or compact the molding material or sand within the flask. For jolting the table 2, there is the jolt piston 12, which is vertically reciprocable within the 50 cylinder 13, the piston and cylinder prefer-

ably having an arrangement such as shown in my co-pending application Serial Number 412,876.

For the purpose of providing a predetermined excess of molding material or sand for 55 the mold and uniformly ramming or compacting this material in the mold, I have provided the frame 14, which is adapted to register with the upper edge of the flask 7 and has a predetermined thickness, so that this frame 60 gauges a predetermined excess of material. This frame is placed upon the flask 7 prior to filling the flask with the molding material and sufficient molding material is heaped up above the flask so that after the molding material has been jolted and thereby rammed or compacted, this molding material still extends above the upper face of the frame so 65 that the amount thereabove may be struck or levelled off by a suitable striker sliding 70 along the upper face of the frame.

To further compact the molding material, the frame 14 is removed from the flask 7 after the molding material has been struck or levelled off and then the bottom board 15 is 75 placed upon the predetermined excess of the molding material. This bottom board is yieldably urged against the molding material under a substantially constant pressure by means of the clamping members 16, each 80 of which is channel-shaped and has an upper leg engageable over the board and a lower leg extending inwardly below the side edge of the base 11 of the table 5. Each clamp is adapted to be urged in a downward direction 85 by means of the piston rod 17 abutting at its lower end the lower flange of the clamp and secured at its upper end to the piston 18, which is slidable within the cylinder 19. Each cylinder 19 is secured at its upper end 90 to the base 11 of the table 5 and depends therefrom and this upper end is closed but provided with a port 20 connected to a suitable supply line for a pressure medium, such as compressed air. It will thus be seen that 95 after the board 15 is placed upon the molding material and the clamping members 16 are placed in position and compressed air is turned on to enter the upper ends of the cylinders, the board will be urged downwardly 100

under a substantially constant pressure, even during the jolting operation, which occurs while the board is thus urged.

It will also be seen that by reason of this arrangement the excess of molding material will be forced into the flask and since it is equally distributed over the area of the flask, the molding material will be additionally rammed or compacted substantially evenly throughout the flask area.

What I claim as my invention is:

1. In a mold jolting apparatus, the combination with a table for supporting a pattern and flask with molding material in the flask extending beyond the latter, a board engageable with the molding material, and means for jolting the table, of means for yieldably urging the board against the molding material extending beyond the flask during operation of the jolting means to compact the molding material within the flask and to clamp the flask to the table.

2. In a mold jolting apparatus, the combination with a table for supporting a pattern and flask, a board, and means for jolting the table, of cylinders mounted upon said table and adapted to receive a pressure medium, pistons slideable within said cylinders, and clamping members engageable with the board when placed upon the molding material and actuated by the pistons for clamping the board against the molding material.

3. In a mold jolting and ramming apparatus, the combination with a table for supporting a pattern and flask with molding material in the flask extending beyond the latter, a board adapted to rest upon the molding material and means for jolting the table, of means engageable with the board and table for clamping the flask to the table, said means including members operable during actuation of the jolting means to exert a yieldable pressure upon the board for urging the molding material toward the flask and to compact the same within the flask.

4. In a mold jolting and ramming apparatus, the combination with a table mounted for rotation and operable to support a pattern and a flask with molding material in the flask extending beyond the latter and means for jolting the table, of means operable during the actuation of the jolting means for exerting a yieldable pressure upon the molding material to urge the same toward the flask and for clamping the flask to the table.

5. In a mold jolting and ramming apparatus, the combination with a rotatable table for supporting a pattern and flask with molding material in the flask extending beyond the latter, and a board adapted to rest upon the molding material, of means engageable with the board and table for clamping the flask to the latter, said means including members operable to exert a yieldable pressure upon the board to urge the molding material

toward the flask, and means for jolting the flask and molding material during operation of the means aforesaid.

6. In a mold jolting and ramming apparatus, the combination with a table for supporting a pattern and flask with molding material in the flask extending beyond the latter and a board adapted to rest upon the molding material, of a clamp having a portion engaging the board and having another portion engaging the table, means for actuating the clamp to cause the latter to exert a substantially constant pressure upon the board for urging the molding material toward the flask and for securing the flask to the table, and means operable during the operation of said clamp for jolting the flask and molding material to further compact the latter within the flask.

7. In a mold jolting and ramming apparatus, the combination with a table for supporting a pattern and flask with molding material in the flask extending beyond the latter and a board adapted to rest upon the molding material, of a clamp having a portion engageable with the board and an adjustable portion engageable with the table, means for actuating the adjustable portion to clamp the flask to the table and for exerting a substantially constant pressure upon the board to urge the molding material toward the flask and thereby compact the same within the flask, and means for jolting the flask and molding material during the operation of said clamp.

In testimony whereof I affix my signature.

JOHN E. RADIGAN.
